Chas. M. Chapman,
ATTORNEY.

UNITED STATES PATENT OFFICE.

EDWARD B. GALLAHER, OF NORWALK, CONNECTICUT.

DUPLEX CONTAINER.

1,290,965.

Specification of Letters Patent. Patented Jan. 14, 1919.

Application filed July 15, 1918. Serial No. 245,099.

To all whom it may concern:

Be it known that I, EDWARD B. GALLAHER, a citizen of the United States, residing in Norwalk, county of Fairfield, and State of Connecticut, have invented a new and useful Improvement in Duplex Containers, of which the following is a description.

This invention has reference to boxes or containers for various commodities and, particularly, has reference to a medium by which valve grinding compounds in several grades may be packed or stored, displayed and dispensed to users in convenient packages and quantities.

15 Among the objects of the invention may be noted the following: to provide a box or container for various commodities which is simple, inexpensive to produce, efficient for the purposes, and capable of carrying

20 two grades of the same class of merchandise, or different classes of merchandise or substances; to provide a duplex package or container in which a valve grinding composition in two grades, having reference to

25 coarseness and fineness, may be packed and conveyed to the general public for use in a convenient and compact form; to provide a medium, for holding valve grinding compounds or compositions, by means of which

30 the contents is prevented from wastage, accidental spilling, can be preserved and protected from grit, dust, dirt, and other foreign substances, and by means of which, when the contents of one part of the medium

35 is being used, the other part can be kept covered and clean; to provide a duplex box or container of such form that it may be placed or put away in the tool-kit of an automobile, either in flat form or doubled

40 into compact form, according to the size or shape of the space or compartment in which it is to be stored; to provide a medium, such as noted in the foregoing, which, when doubled into smaller or compact form, can

45 be made to retain such form and the contents used from first one end and then the other with all the advantages set forth in the foregoing; to provide a duplex can, box or container for various substances, such as a

50 valve grinding composition, which primarily and normally has a flat form, but which can be folded into cylindrical form so as to produce a compact and smaller package the contents of which can be ex-

55 tracted from opposite ends; to provide a box or container, such as set forth in the

foregoing which is convenient to handle, can be handled without soiling the hands, and which enables the user to utilize the entire contents without waste; and to provide a duplex container which can be readily secured temporarily and detachably to a card or rack for display and advertising purposes, and which card may be used as a separating medium in the carton in which quantities are packed for transportation.

With the above objects in view, and others which will be detailed during the course of this description, my invention consists in the parts, features, elements and combinations thereof hereinafter described and claimed.

In order that my invention may be clearly understood, I have provided drawings wherein:

Figure 1 is an elevation of a duplex structure embodying a form of the invention which is deemed sufficient to disclose its nature, one end of the figure being broken away to show details;

Fig. 2 is a top plan of Fig. 1;

Fig. 3 is an elevation of the structure when doubled into compact, cylindrical form;

Fig. 4 is a top plan showing a plurality of containers on a display or sample card; and

Fig. 5 is a side elevation of Fig. 4.

Referring to the drawings, the numeral 1 indicates the base of the duplex structure, 2 one of the boxes or receptacles, 3 the cover thereof, 4 the companion and similar box or receptacle, and 5 the cover thereof.

The base or connecting medium 1 is, preferably, formed of a single strip of thin, flexible, metal of a size and shape adapted to support the two boxes or receptacles, and, at its opposite ends, conforms to the circumference or periphery of the boxes or receptacles, thus avoiding sharp edges or corners. The base 1 is provided transversely, midway between its ends, with a suitable medium 6 by which to indicate where and how it may be folded or bent if desired. The medium 6 may be merely a mark on the surface, or it may be a groove, rib or depression, as shown in Fig. 1. The metal should be sufficiently heavy or stiff to support the filled boxes without bending when the container is held by one end; but, thin and light enough to readily bend on the median line 6 when light pressure is produced upon one or the other end thereof to bend one box back against the other.

The boxes or receptacles may be secured to the opposite ends of the base or connecting medium in any way which is found to be convenient, expeditious, and to be sufficiently strong, as, for example, by spot soldering. Preferably, the two boxes or receptacles are spaced apart sufficiently on the base, as shown in Figs. 1 and 2, relatively to the medium 6, to enable the caps or covers to be readily applied and removed without interfering with each other. As shown in the drawings, the boxes or receptacles are, at their free ends, screw-threaded, as at 7, and the caps or covers thereof are correspondingly screw-threaded, as at 8, so as to be readily turned thereon and held frictionally. By screw-threaded, I mean that the parts are given the form of a screw-thread, not necessarily having the screw-threads turned in their corresponding or coöperating surfaces. This may be accomplished by stamping or in any other expeditious or economical way; but, I desire it understood that my invention is not confined to this form of cover or closure. Any other suitable form may be employed that can be quickly set or adjusted in place and quickly removed, and which may be found sufficiently tight for the purpose.

From the foregoing description, it will be understood that I have provided a compact, convenient and simple medium by which various commodities may be placed upon the market and, particularly, by means of which valve grinding composition in two grades can be packed, stored, and sold.

The container can be packed in flat form, as shown in Fig. 1, in cartons or boxes in any desired number, or it may be folded or turned back on the median line 6 into the cylindrical form shown in Fig. 3, thus reducing its length and enabling it also to be stored in the tool-box of an automobile or in small space. It may also be primarily bent into this form and flattened out when required for use. When bent into the form of Fig. 3, it may be quite rigidly held thus by bending over the angular portions 9 on opposite sides in either direction, as shown in Fig. 3, this operation quite securely locking the two boxes or receptacles together. The lines on which the portions 9 may be bent are shown in Fig. 2.

I may also make up sample packages, for display or advertising purposes, of three or more boxes, containers, or receptacles on a single holder or card of stiff material 10, from which the boxes or receptacles may be removed as desired by releasing flexible clips 11 which may be bent over to attach or detach the duplex containers. The clips 11 are made integral with the base 1, being cut out or struck up therefrom during the operation of stamping out the base. Thus, it will be seen that I may attach a plurality of con-

tainers or receptacles 2, 4, and or a plurality of duplex containers, to a base, according to the objects to be accomplished. The card or holder 10 is also a convenient and very useful means by which to handle the containers in bulk and to pack the same in cartons for transportation; and said card also acts as a separation medium between series of containers in a large carton to prevent them from becoming scratched, marred, or otherwise injured in handling and transportation. The card 10 may carry or have printed thereon at opposite ends, or elsewhere, any desired advertising matter; and the size of the card may be increased as desired to carry more containers or become a medium for display and advertisement of the containers.

Having thus described my invention, what I claim and desire to secure by Letters Pat- 85 ent is:

1. A container comprising a flat, flexible base or support and a plurality of separate and independent boxes or receptacles each provided with a closure or cover, said boxes 90 being rigidly secured by their bottoms only to said base or support.

2. A container, for holding different grades of material, comprising a base or support having mounted thereon two independent receptacles, the latter being spaced apart sufficiently to enable their covers to be readily applied and removed, the said base being formed of flexible material, whereby it may be bent between the receptacles to bring 100 the latter into superposed relation.

3. In combination, a flexible base or support, a pair of receptacles rigidly secured thereto, said base having between the receptacles a medium along which the same may 105 be bent to change the relation of the receptacles.

4. In combination with a holder; means for carrying different commodities, or different grades of the same commodity, comprising a plurality of boxes or receptacles, and a supporting base for the latter, said boxes being arranged on the base in spaced apart relation; and said base and holder having means by which the boxes may be 115 detachably carried by the holder.

5. A duplex container comprising a base; two boxes secured to said base in spaced apart relation; the base being provided with means permitting it to be bent between the 120 boxes so as to bring the latter into superposed relation and convert the container from flat form to cylindrical form.

6. A duplex container comprising a flexible base; two boxes secured to said base in 125 spaced apart relation, whereby the base may be bent or folded between said boxes so as to bring the latter into superposed relation, and convert the container from flat form to cylindrical form.

7. A duplex container comprising a flexible base; two boxes secured to said base in spaced apart relation, whereby the base may be bent or folded between said boxes so as to bring the latter into superposed relation, and convert the container from flat form to cylindrical form, and said base having means by which the cylindrical form of the container may be held.
- 10 8. A duplex container comprising a flexi-
ble base; two boxes secured to said base in spaced apart relation, whereby the base may be bent or folded between said boxes so as to bring the latter into superposed relation, and convert the container from flat form ¹¹ to cylindrical form, and said base having means by which the boxes may be locked in superposed relation.

EDWARD B. GALLAHER.
